Des. 215,810
Patented Nov. 4, 1969

215,810

ELECTRICIAN'S TOOL

Eugene D. Hindenburg, Sycamore, Ill., assignor to Holub Industries, Inc., a corporation of Illinois

Filed Feb. 10, 1969, Ser. No. 15,732

Term of patent 14 years

Int. Cl. D8—02

U.S. Cl. D8—58

FIGURE 1 is a plan view of the electrician's tool, showing my new design, with the tool being illustrated in its closed position;

FIGURE 2 is a view of the tool as shown in FIGURE 1, with the tool shown in an open position;

FIGURE 3 is a bottom plan view of the tool as shown in FIGURE 1;

FIGURE 4 is a view of the tool taken substantially along line 4-4 of FIGURE 1; and

FIGURE 5 is a view taken substantially along line 5-5 of FIGURE 4.

I claim:

The ornamental design for an electrician's tool, substantially as shown and described.
